UNITED STATES PATENT OFFICE

2,683,338

RAZOR CONDITIONER

Reinhold O. Nuss, Spokane, Wash.

Application February 2, 1953, Serial No. 334,388

5 Claims. (Cl. 51—212)

1

This invention is a conditioner for cutting edges such as is common to a straight-edge razor.

One object of the invention lies in the provision of a conditioner which will very effectively condition the cutting edge of a straight-edge razor or similar article with a minimum amount of effort.

Another object of the invention lies in the provision of a conditioner which uses a mild steel plate having a plane polished upper face upon which the cutting edge of an implement may be conditioned.

Another object of the invention lies in the provision of a mild steel conditioning plate carried by a base and united therewith by means of a resilient layer interposed the plate and base and adhesively secured thereto.

Another object of the invention lies in the provision of a conditioner including a mild steel plate having a body hardness selected from a group within the Brinell hardness scale ranging from 101 through 140.

Another object of the invention lies in the provision of a conditioner which is inexpensive to manufacture and which is not liable to become inoperative by much use.

These and other objects of the invention will become apparent during the course of the following description.

In the accompanying drawings, forming a part of this specification, and in which like numerals are employed to designate like parts,

Figure 1 is a perspective view of the preferred embodiment of my improved conditioner showing a straight-edge razor associated therewith in full line and the method of sharpening indicated by full and dotted arrows; and

Figure 2 is a fragmentary enlarged vertical cross section taken through the conditioner.

The present invention is applicable to sharpening knives and other shearing or cutting implements and even though I limit my description of the invention as it relates to sharpening straight-edge razors, it is not my intention to unduly restrict the scope of my patent to any particular use and I desire to secure my invention for any and all uses of which it is susceptible.

It is the present practice of those who sharpen straight-edge razors and similar implements to use carborundum blocks or other fine abrasives for honing the edge of the razor.

In the instance of knives and the like, it is sometimes the practice to use a metallic file for sharpening the edge, but where it is desired to have a truly fine or sharp cutting edge, honing and stropping is the accepted practice.

2

The most common hone known to me is one defined as being approximately 118 grit, where the finest hone to my knowledge is 159 grit. A razor after being honed on one of these hones can never be immediately used for shaving, but must be stropped by applying each side of the cutting edge to a strop twelve to fifteen strokes. Even with these time-consuming and arduous tasks, the cutting edge of the razor is not as sharp as is desirable nor as sharp as is possible.

Another objection to the present day hones is that the pores of the hones fill up with steel from the razor and the cutting quality is thereby changed, making it impossible for the one honing the razor to determine the amount he has honed the edge without microscopic inspection.

My present invention avoids these defects and provides a conditioner which when properly used will condition the blade edge of a straight-edge razor so that without stropping it may be used for shaving.

As indicated in the drawing, the conditioner comprises a plate 10 which is approximately two inches by four inches in plan and one-fourth of an inch thick. The plate is mild steel, the analysis of which is not of great importance; however, in the models I have made and tested the carbon content of the mild steel was from 18% to 20%. I do not wish to be limited by this disclosure since the important feature required in the steel is its relative degree of hardness, not necessarily its carbon content. I have found the steel having a hardness approximately No. 120 in the Brinell scale as being the most effective for conditioning the edge of a razor; however, steels within the Brinell scale in a group ranging from 101 through 140 will function to a greater or lesser degree.

The thickness of the mild steel plate 10 is of little consequence relative to the conditioning surface 11 except that it is required that the surface be planished and it must be of a true unvarying plane. For this reason I have found that a quarter-inch plate effectively prevents warping of the surface 11 and for economic reasons is most acceptable for this invention. However, a thinner plate may be employed if it is suitably reinforced to prevent the surface 11 from becoming uneven.

As shown in the drawing, the plate 10 is supported by a base 12 indicated to be of a synthetic resin material. The base may be formed of wood or other relatively light-weight material which will provide adequate thickness to the conditioner to permit one to properly hold it in his hand and yet will preclude its being too heavy for proper manipulation, since it is anticipated that a con-

ditioner of this type will be used in barber shops as well as in other shops and homes.

The conditioner undoubtedly will be placed upon a hard, unyielding surface and, therefore, it is necessary that a resilient layer, indicated in general by the numeral 13, be interposed the plate 10 and base 12. This may be done by vulcanizing a layer of rubber 14 to the plate and securing the rubber to the base 12 by means of an adhesive agent 15, or an adhesive agent which includes a resilient body constituent may be used to secure the plate 10 to the base 12, thus omitting the rubber layer 14.

In using my conditioner, a razor R or other cutting instrument having its edge in good shape; that is, without large nicks or dents, is placed upon the planished face 11 with its back b adjacent one end of the conditioner and parallel thereto and its edge e toward the opposed end. The razor is then drawn across the conditioner at approximately a 45° angle with its edge e leading. The razor is then turned over so the opposite side of the blade is placed upon the conditioner as shown in dotted lines and is moved as shown by the dotted arrows. This conditioning movement will be repeated from five to ten times, depending upon the previous condition of the razor, after which the razor may be immediately used for shaving. It does not injure the cutting edge e to strop it after this conditioning action; however, this stropping improvement is barely perceptible over the conditioned razor.

It is to be understood that no abrasive is used in the plate 10 and I assume that the reason for the improvement of the cutting edge is that the microscopic teeth present on every cutting edge will be conditioned or straightened to the extent that they improve the cutting qualities of the razor above that which can be derived from honing and stropping.

Having thus described my invention, I claim:

1. A razor conditioner comprising a plate of mild steel having a plane upper face; a thickened relatively light weight base commensurate in plan dimensions to the plate; and a layer of resilient material intermediate said plate and base and adhesively secured thereto.

2. The invention as defined in claim 1 wherein the mild steel is one selected from a group within the Brinell hardness scale ranging from 101 through 140.

3. The invention as defined in claim 1 wherein the hardness of the mild steel is substantially 120 Brinell.

15 4. A razor conditioner comprising a plate of mild steel having a plane upper face; a thick relatively light weight base commensurate in plan dimension to the plate; a layer of rubber vulcanized to the lower face of said plate; and an adhesive agent tenaciously uniting the base and layer.

20 5. A razor conditioner comprising a plate of mild steel substantially one-quarter of an inch in thickness; and a thick relatively light weight base adhesively secured to said plate by means of a layer of an adhesive agent including a resilient body constituent.
